PUMPING UNIT

August R. Maier, Dallas, Tex., assignor to Oil
Well Supply Company, Dallas, Tex., a corpo-
ration of New Jersey

Application May 3, 1935, Serial No. 19,714

2 Claims. (CL 74—41)

My present invention relates to improvements in pumping units for pumping wells such as petroleum wells and particularly to improvements on a twin crank pumping unit described and 5 claimed in my Patent 1,972,660, of September 4, 1934.

In said Patent 1,972,660, a pumping unit is described in which one arm of a walking beam is connected at one end to sucker rods that extend 10 into the well to a pump located in the bottom of the well and the other arm is connected to a power device by means of a pair of pitmans or connecting rods one on each side of the walking beam. The pitmans are connected to the walking beam by means of an equalizing bar that may rock in a vertical plane transverse to the axis of the walking beam. The pitmans are mounted 15 on the equalizing bar by spherical surface bearings that permit the equalizing bar to tilt relative to the pitman throughout a limited range. The pitmans are similarly connected by spherical- 20 ly shaped bearings to a crank on the power supply unit. This provides compensation for any warping of the pumping unit that may take place 25 in the field where such pumping units may be subjected to severe usage.

The stresses imposed on pumping units of the above type is very great inasmuch as in pumping deep wells a weight of several thousand pounds may be suspended on the sucker rod arm of the walking beam. Consequently, if one of the pitmans should break, this great weight on the sucker rod arm would tend to depress the latter to its lowest point and, if the transverse equalizing bar were then permitted to rock freely, it would tilt throughout a relatively large angle, which would tend to break the bearing of the unbroken pitman and might strike the walking beam with great momentum at some part of its rotation. The smashing effect on the pumping unit by the impact of the power and momentum of the pumping unit might in such cases 35 wreck the entire unit.

The danger of a possible wreckage of the pumping unit by a breakage of one pitman is obviated or lessened by my present invention, which provides a means whereby, upon the breakage of one pitman, the weight on the sucker rod arm is suspended on the opposite pitman which continues to rock the walking beam in the normal 45 manner.

The various features of the invention are illustrated in the accompanying drawing, in which—

Fig. 1 is a vertical section through a walking

beam and equalizing bar embodying a preferred form of the invention; Fig. 2 is a plan view of the equalizing bar and mounting therefor; and Fig. 3 is a vertical section taken on line 3—3 of Fig. 1.

In the construction shown in the accompanying drawing, the arrangement of the pitmans, walking beam and equalizing bar is similar to the arrangement described generally in Patent 1,972,660. In this construction, a mounting or 10 seat 10 is provided on the upper flange of the walking beam 11 and carries a pintle or supporting shaft 12 extending longitudinally of the walking beam. An equalizing bar 13 is mounted on the shaft 12 and extends on opposite sides 15 of the beam 11. Each end of the equalizing bar 13 is provided with a bearing shell 14, on which is mounted a strap or housing 15 of the respective pitman 16, so that the equalizing bar 13 may rock in a vertical plane throughout a limited angle without tending to twist or distort the 20 housings 15. Suitable lubricating means are provided, as described in Patent 1,972,660.

In the event that either of the pitmans 16 should break, the equalizing bar 13 would tend to be 25 pulled downwardly by the opposite pitman relatively to the walking beam 11. Or, otherwise stated, the weight on the sucker rod arm of the walking beam would tend to lift the seat 10 relative to the unbroken pitman and thus tend to rock 30 the equalizing bar to such an extent as to twist or distort the housing 15, and possibly break it. This would cause the pitmans to rotate like flails and cause additional damage.

In my present invention, I provide stops on 35 the walking beam which will limit the rocking of the equalizing bar to a limit slightly beyond that provided for in normal usage, so that upon a breakage of either pitman the equalizing bar will rest on a stop and be operated by the remaining pitman. In the particular embodiment of the invention shown in the accompanying drawing, these stops are provided by upturned edges 17 at the sides of the seat 10, against which the undersurface of equalizing bar 13 will 45 rest when the opposite end of the equalizing bar is released by the breakage of a pitman. With the above arrangement, when either pitman breaks, the weight on the sucker rod arm of the walking beam will lift the power arm and the 50 seat 10 upwardly until the stop 17 comes into contact with the undersurface of the equalizing bar. The weight on the sucker rod arm will maintain the stop 17 in contact with the undersurface of the equalizing bar and thereafter the walking 55

beam will be operated by the unbroken pitman until stopped by the operator for repairs.

For example, in a pumping unit in which the maximum rocking provided for the equalizing bar is five degrees, the stop 17 will be so positioned that a tilting of the equalizing bar slightly beyond five degrees will cause the bar to rest on a stop 17.

Through the above invention, it will be apparent that the dangers of wreckage caused by a breaking of a pitman will be greatly diminished, if not entirely removed.

What I claim is:—

1. A pumping unit which comprises a walking beam, an equalizing bar mounted to rock on said walking beam in a vertical plane transverse to

the length of said beam, a pair of pitmans, one for each end of said equalizing bar and a stop to limit the rocking of said equalizing bar upon breakage of either of said pitmans.

2. A pumping unit which comprises a walking beam, a transverse equalizing bar mounted on said walking beam to rock in a vertical plane transverse to the length of said walking beam, spherical surfaced bearing shells on the ends of said equalizing bar, pitmans, one for each end of said equalizing bar mounted on said shells and a pair of stops one at each side of said walking beam to contact with the lower surface of said equalizing bar when the latter tilts beyond a predetermined angle.

AUGUST R. MAIER.
